UNITED STATES PATENT OFFICE

CHARLES A. DICKHAUT, OF NEW BRUNSWICK, NEW JERSEY, ASSIGNOR TO JOHN WAL-
DRON CORPORATION, OF NEW BRUNSWICK, NEW JERSEY, A CORPORATION OF NEW
JERSEY

AUTOMATIC SIDE CONTROL FOR ROLLS

Application filed June 18, 1930. Serial No. 461,891.

This invention relates to a mechanism adapted to be used in the manufacture and handling of sheet materials such as paper, cloth and the like which are manufactured in 5 long strips or webs.

In the manufacture of materials of this type, some steps in the manufacturing operation require winding the sheet or web material into rolls in order to facilitate handling.

10 When the web is fed from the roll to a subsequent operation, it is desirable, and in fact necessary, for it to follow a predetermined path. This is particularly true when the web is fed to a cutting machine or to some other 15 operation which requires rewinding the web since in the latter instance it is desirable that the edges of adjacent turns coincide. As irregularities often occur in the edges of the strip, due to uneven shrinking or stretching, 20 steps must be taken to guide properly the path of the traveling sheet from one operation to the next.

An object of this invention is to compensate for lateral deviation of the web in passing from one operation to another.

Another object of the invention is to compensate for lateral deviation during the travel of the web by controlling its path in accordance with the contour of its edges.

25 Still another object of the invention is to determine the path of a traveling sheet having an associated roll by adjusting the roll longitudinally of its axis in accordance with the contour of the sheet edge.

30 A further object of the invention is to prevent the operation of the controlling means when the true edge of the web has been mutilated, as for instance, when a portion has been inadvertently torn during manufacture or handling.

Another object of the invention is to reduce the cost of manufacturing web materials of this type by providing for the adjustment of a plurality of rolls from a common actuating 45 element.

Still another object of the invention is to reduce the strain on some of the elements of the apparatus employed, thereby reducing replacement costs.

50 A feature of the invention resides in a

chamber having a flexible diaphragm to which a lever arm or other equivalent device is affixed. The lever arm or its equivalent is adapted to displace the roll upon which the sheet is wound longitudinally of its axis, 55 which displacement is determined by the pressure in the chamber heretofore mentioned. This pressure is in turn determined by the position of the edge of the traveling web.

Another feature of the invention resides in providing a pair of chambers for each roll, the pressure in each of which is controlled by a different edge of the web. The diaphragms of each pair are connected together and both function simultaneously to transmit longitudinal displacement to the roll. This arrangement permits the pressure on the diaphragms to be balanced under normal 65 conditions, thereby reducing the strain and considerably increasing the life of the diaphragm.

Another feature of the invention resides in means whereby the control chambers of a plurality of rolls may be connected to a common means for maintaining a normal chamber pressure while at the same time changes of pressure in one chamber are isolated and prevented from affecting the others.

70 A better understanding of the invention 80 may be had by reading the following description together with the accompanying drawings wherein,

Fig. 1 is a diagrammatic view illustrating a plurality of rolls simultaneously controlled. 85

Fig. 2 is a diagrammatic view at right angles of Fig. 1 showing a single control chamber.

Fig. 3 is a view similar to Fig. 2 wherein a double control chamber is used.

80 Figs. 4, 5 and 6 are enlarged views showing structural details of the invention.

Referring now to Fig. 1, a frame element 1 is shown supporting a plurality of rolls 2 of sheet material such as paper web or the like. From each of the rolls the web 3 is fed over a guide roller 4 between another pair of guide rollers 5 and 6 to a cutting machine or machine for performing some other operation, which machines are not shown. As men- 95

tioned heretofore, it is quite necessary that the web material be fed to each subsequent operation in a perfectly straight line, but due to irregularities in the edges of the strips from uneven shrinking or stretching, this desirable result may not always be accomplished unless some means are provided to compensate for such irregularities.

In accordance with this invention, a finger element 7 is suitably positioned to contact with the traveling sheet so that its position is determined by the edge of the latter. The finger element 7 actuates a valve element 8 of a type similar to that disclosed in my Patent No. 1,634,984 issued July 5, 1927. Briefly, the valve shown in this patent comprises an aperture opening to the atmosphere an amount determined by the position of the contact finger 7.

Connecting the valve 8 and a pressure chamber 9 is a tube or duct 10 by means of which the pressure of fluid in the chamber is controlled in accordance with the opening of the valve 8. The pressure in the chamber 9 is preferably, although not necessarily, below atmospheric and is maintained at a substantially constant value by a vacuum pump 11. This vacuum pump is connected to the chamber through the duct 12, and the T connections 13 and 14. An enlarged view of the T connection 14 is shown in Fig. 5. The tube 15 leading from the main duct 12 is throttled down so that only a small passageway 16 communicates with that portion of the tube leading to the diaphragm chamber and the valve 8. The purpose of this will be evident hereinafter.

The vacuum chamber 9 is fixedly mounted on the frame 1. Its face is closed by a flexible diaphragm 18, the movement of which provides the adjustment of the roll 2. For this purpose, a rod 19 is pivoted at 20 to a lever 21 which in turn is pivoted at 22 to a rigid arm 23, permanently secured to the framework 1 or the chamber 9. The upper end of the arm 21 terminates in a U member 24 from which pins 25 project inwardly and engage in a groove 26 in the collar 27. The collar 27 is fixedly secured to the shaft 29 upon which the roll 2 is mounted. The shaft 29 is free to slide in the bearing 30. A tension spring 31 suitably anchored at 32 opposes the force acting on the diaphragm 18 and normally exerts a force which holds the diaphragm undistended when the sheet is traveling in its proper path.

In order to prevent excess wear on the diaphragm 18 when the vacuum in the chamber 17 is such that the diaphragm is distended to its maximum position inwardly, a safety valve is provided as shown in Fig. 4. This valve comprises a spindle 33 and a valve 34 normally held in closed position by the spring 35 butting against the outer side of the valve 34 and the inner face of the cap 36. A hole 37 in the cap 36 communicates with the cham-

ber 38 so that when the valve 34 is displaced, the chamber 7 is in direct communication with the atmosphere. Thus, when the roll 2 has its maximum longitudinal adjustment in one direction, the end of the rod 19 will butt against the spindle 33 tending to unseat the safety valve and relieve the vacuum in the chamber 17. This prevents a greater vacuum in the chamber than is required for maximum longitudinal adjustment of the roll and thereby prevents undue strain on the diaphragm 18.

In operation the vacuum pump 11 tends to maintain a suitable constant vacuum in all of the vacuum chambers 9. This pressure is so regulated that the diaphragm is in its mid or undistended position when the valves 8 are half open. The finger 7 is held in contact with the edge of the web 3 by a spring, not shown but which is described in my patent referred to above. If there is an irregularity in the edge of the paper, it displaces the finger 7 opening or closing the valve 8, as the case may be, depending upon the direction in which the finger is displaced. If the valve is opened, the vacuum in the chamber 9 will be lowered, thereby permitting the diaphragm 18 to distend outwardly. The spring 31 will thereupon rotate the lever 21 slightly, displacing the unwinding roll 2 to the right (Fig. 2) to compensate for the unevenness of the sheet edge. If, on the contrary, the finger 7 moves to close the valve 8, the vacuum in the chamber 9 will be increased, thus drawing the diaphragm 18 inwardly against the tension of the spring 31, whereupon the roll 2 is displaced to the left (Fig. 2) and the irregularity of the edge of the strip in this direction likewise compensated.

In order to prevent the operation of one of the plurality of valves 8 from affecting all of the vacuum chambers 9, the duct 15 leading from the passage 10 between the vacuum chamber and the valve is throttled down as shown in Fig. 5. This permits one of the valves 8 to be opened affecting immediately its associated vacuum chamber and diaphragm although practically no effect will be evidenced in the common duct 12 leading from the vacuum pump 11 to all of the vacuum chambers.

Another embodiment of the invention is shown in Fig. 3. Herein a pair of balanced vacuum chambers 50 and 51 are used, which eliminate the use of a spring and also tend to prolong the life of the diaphragms. The vacuum chambers 50 and 51 are identical with those already described and communicate with a vacuum creating means through tubes 52 and 53 respectively. A single rod 54 is connected at its extremities to the diaphragms of the chambers 50 and 51. At the centre of the rod 54 is pivoted a lever arm 55, which in turn is pivoted at 56 to the stationary cross member 57. As in Fig. 2 the upper

end of the lever 55 is U-shaped and has projecting pins which engage in the groove 58 of the collar 59. The shaft 60 and the bearing 61 correspond respectively to the shaft 29 and the bearing 30 of the embodiment previously described. The vacuum chamber 50 is connected through a duct 62 to a valve and its associated finger, contacting one edge of the traveling sheet while the duct 63 connects the other chamber 51 to a valve and associated finger, contacting the opposite edge of the traveling sheet.

The operation of this embodiment of the invention will be apparent from the following discussion. If the web unwinding from the roll 2 is displaced in one direction as, for instance, to the left in Fig. 3 the finger contacting the right edge of the sheet will tend to close the valve associated therewith, whereas the finger contacting the left edge of the sheet will cause its associated valve to open. This will increase the vacuum in the chamber 50 and decrease the vacuum in the chamber 51. Rod 54 will be displaced longitudinally to the left with a corresponding displacement of the roll 2 to the right, thereby compensating for the lateral displacement of the web. In this way, the web is maintained in a straight path. It is obvious that when this embodiment is used, the force necessary to displace the roll longitudinally is divided equally between the diaphragm chambers 50 and 51, thereby requiring only half of the force ordinarily exerted by such a chamber. This materially decreases the strain on the diaphragms associated with these chambers and greatly prolongs their life.

In Fig. 6 another type of contact finger is shown, which may be used if desired in place of the one shown in Fig. 1. An arrangement of this type is used in order to prevent portions which have been inadvertently torn from the traveling sheet from actuating the control mechanism. This type comprises a pair of fingers 70 and 71 which are adapted to contact with the edge of the traveling strip. These fingers are rigidly secured to the cross arm 72, the latter in turn being rigidly secured to the rod 73, which is an element of the control valve described in my Patent No. 1,634,984 above referred to. Due to the fixed relation of the fingers 70 and 71 and the rod 73, it is obvious that the fingers 70 and 71 must function as a unit to operate the valve 8. These fingers are positioned sufficiently far apart so that inadvertent mutilations of the edge of the traveling sheet in contact with one finger will not extend to the other; thus when one finger is adjacent a mutilated portion, the other finger will contact with the true edge of the strip. In such a case, the latter is the only finger controlling the valve 8 in consequence of which the mutilated edge has no effect in adjusting the position of the roll.

In describing this invention, the several embodiments have been discussed simply by way of example and it is to be understood that the invention is not limited thereto. Thus, although the longitudinal positions of the rolls described are adjusted in accordance with the edge of the strip as it unwinds from the roll, it is quite obvious that a similar control may be employed in combination with a traveling sheet winding up on a roll. Furthermore, the control is capable of use with a plurality of guide rollers between which the sheet may be caused to travel. In fact, the invention is considered sufficiently broad to cover any arrangement for longitudinally adjusting a roll with which a traveling sheet is associated in any manner whatsoever, and is to be limited only by the prior art and the scope of the appended claims.

Having described my invention, what I claim as new and desire to secure by Letters Patent, is:

1. In a device for adjusting the paths of a plurality of traveling sheets, each having an associated roll, the combination with said rolls of individual fluid operated means for adjusting the position of said rolls, and means common to said fluid operated means for maintaining the pressure thereof.

2. In a device for adjusting the path of a plurality of traveling sheets, each having an associated roll, the combination therewith of individual vacuum means for adjusting the position of said rolls, and an element common to a plurality of said vacuum means for creating the vacuum therein.

3. In a device for adjusting the paths of a plurality of traveling sheets, each having an associated roll, the combination therewith of individual vacuum means for adjusting the position of said rolls, an element common to said vacuum means for creating the vacuum therein, and means associated with each of said vacuum means for substantially confining variations in vacuum pressure to the vacuum means with which it is associated.

4. In a device for adjusting the paths of a plurality of traveling sheets, each having an associated roll, the combination therewith of individual vacuum means for adjusting the position of said rolls, an element common to said vacuum means for creating said several vacuums, and throttling means associated with each of said several vacuum means for substantially preventing variations of vacuum therein from affecting said other vacuum means.

5. In a device for adjusting the paths of a plurality of traveling sheets, each having an associated roll, the combination therewith of individual vacuum means functioning to adjust said rolls longitudinally of their axes in accordance with the edge of their associated traveling sheets, common means for creating said several vacuums, and means in-

- terposed between each of said vacuum means and said common means for substantially preventing variations in pressure of any one from affecting any of the others.
6. In combination, a roll of sheet material mounted for rotation about its longitudinal axis, a vacuum chamber having a diaphragm associated therewith and means actuated by said diaphragm for imparting longitudinal adjustment to said roll.
10. 7. In combination, a roll of sheet material mounted for rotation about its longitudinal axis, a vacuum chamber having a diaphragm associated therewith, responsive to variations of pressure therewithin, means directly controlling the pressure in said chamber in accordance with the position of the unwound portion of said sheet, and means actuated by said diaphragm for adjusting said roll longitudinally of its axis.
15. 8. In combination, a roll of sheet material mounted for rotation about its longitudinal axis, a vacuum chamber having a diaphragm associated therewith responsive to variations of pressure in said chamber, a valve associated with said chamber and communicating directly with the atmosphere, means controlling the opening of said valve in accordance with the position of the unwound portion of said sheet, means actuated by said diaphragm for adjusting said roll longitudinally of its axis, and means for opposing the action of said diaphragm.
20. 9. In combination, a roll of sheet material mounted for rotation about its longitudinal axis, a plurality of vacuum chambers, diaphragms associated with each of said chambers and responsive to variations of pressure therein, a valve associated with each of said chambers communicating directly with the atmosphere and means actuated by both of said diaphragms for adjusting said roll longitudinally of its axis.
25. 10. In combination, a roll of sheet material mounted for rotation about its longitudinal axis, a pair of vacuum chambers, each having a flexible diaphragm normally balanced against the other, and means for adjusting said roll along its longitudinal axis an amount determined by the unbalanced forces acting on said diaphragms.
30. 11. In combination, a roll of sheet material mounted for rotation about its longitudinal axis, a pair of vacuum chambers, each having a flexible diaphragm normally balanced against the other and responsive to variations of pressure in its respective chamber, means for controlling the pressure in said vacuum chambers in accordance with the position of the unwound portion of said roll, and means for adjusting said roll along its longitudinal axis in accordance with the difference of pressure in said chambers.
35. 12. In combination, a roll of sheet material mounted for rotation about its longitudinal axis, a pair of vacuum chambers, each having a diaphragm responsive to variations of pressure in its respective chamber, means connecting said diaphragms, means for controlling the pressure in said vacuum chambers in accordance with the contour of opposite edges of an unwound portion of said roll, and means for determining the position of said roll in accordance with the difference in pressure in said chambers.
40. 13. In combination, a roll of sheet material mounted for rotation about its longitudinal axis, a vacuum chamber, means for adjusting said roll longitudinally of its axis in accordance with the pressure of said chamber, means contacting one edge of an unwound portion of the sheet whereby the pressure in said chamber is controlled in accordance with the contour of the edge of said sheet, said contacting means comprising a plurality of spaced fingers.
45. 14. In combination, a roll of sheet material mounted for rotation about its longitudinal axis, means for adjusting said roll longitudinally of its axis in accordance with the edge of an unwound portion of said roll, and means for preventing the operation of said adjusting means when a mutilated portion of the sheet is in contact therewith.
50. 15. In a device for adjusting the path of a plurality of sheets each having an associated roll, the combination therewith of individual fluid control means for adjusting the position of said rolls, common means for creating a suction within said fluid control means, a valve associated with each of said control means permitting variations in pressure therewithin, a duct connecting said control means with its associated valve, and an aperture of substantially smaller area than said duct between said individual control means and the suction creating means.
55. 16. A plurality of pressure chambers, common means for maintaining a substantially uniform pressure in said chambers, means individually responsive to the pressure in each of said chambers, and means for substantially isolating pressure variations in each of said chambers from the remainder thereof.
60. 17. A plurality of pressure chambers, common means for maintaining a substantially uniform pressure in said chambers, means individually responsive to the pressure in each of said chambers, and throttling means for substantially isolating pressure variations in each of said chambers from the remainder thereof.
65. 18. In a device for adjusting the path of a traveling sheet, the combination therewith of a roller with which the sheet is associated, a pressure chamber having a flexible diaphragm, means for imparting the movement of said diaphragm to adjust said roll longitudinally of its axis, and means actuated in accordance with the edge of said traveling

sheet for adjusting the pressure on said diaphragm.

19. In a device for adjusting the path of a traveling sheet, the combination therewith of a roll with which the sheet is associated, vacuum means for adjusting said roll longitudinally of its axis, and means for relieving the vacuum within said vacuum means at the limit of adjustment of said roll.
- 10 20. In a device for adjusting the path of a traveling sheet, the combination therewith of a roll with which the sheet is associated, vacuum means for adjusting said roll longitudinally of its axis, and a release valve in said vacuum means functioning at the limit of adjustment of said roll.

In testimony whereof I affix my signature.
CHARLES A. DICKHAUT.
